[57] CLAIM

The ornamental design for the combined grill and table, as shown and described.

DESCRIPTION

FIG. 1 is a perspective view of a combined grill and table showing my new design;

FIG. 2 is a top plan view thereof;

FIG. 3 is a front elevational view thereof;

FIG. 4 is a left side elevational view thereof, the opposite side being a mirror image;

FIG. 5 is a rear elevational view thereof;

FIG. 6 is a bottom plan view thereof; and,

FIG. 7 is a perspective view thereof with the cover added.

The cover is removed in FIGS. 1-6 for clarity of illustration.

FIG. 1**FIG. 2****FIG. 3****FIG. 4****FIG. 5****FIG. 6****FIG. 7**
